M. ROTHSCHILD

TEXTILE FABRIC

Filed Dec. 5, 1922

Max Rothschild, INVENTOR.

BY

Sidney R. Perry ATTORNEY.

UNITED STATES PATENT OFFICE.

MAX ROTHSCHILD, OF NEW YORK, N. Y., ASSIGNOR TO SUSQUEHANNA SILK MILLS, A CORPORATION OF NEW YORK.

DESIGN FOR A TEXTILE FABRIC.

Application filed December 5, 1922. Serial No. 4,498. Term of patent 3½ years.

To all whom it may concern:

Be it known that I, MAX ROTHSCHILD, a citizen of the United States of America, and resident of the city of New York, county of New York, and State of New York, have invented a new, original, and ornamental Design for a Textile Fabric, of which the following is a specification, reference being had to the accompanying drawing, forming part thereof.

The figure is a plan view of a textile fabric, illustrating my new and ornamental design.

I claim:

The ornamental design for a textile fabric as shown.

MAX ROTHSCHILD.

Witnesses:

ALBERT C. SCHNITZINGER,

HENRY C. BORGER.
